ABSTRACT

Each of two aluminum bar sections has a pair of laterally spaced parallel side members with inner surfaces facing the inner surfaces of the other pair, and a pair of loop members disposed side by side in the space between the side members. One loop member has ends integral with the side members of one bar section and projects from the outer faces of the other pair of side members. The other loop member has ends integral with the side members of the other bar section and projects from the outer faces of the side members of the first section, whereby the loop members form recesses opening laterally in opposite directions and disposed end to end to lock the two bar sections together when a rod is inserted lengthwise into the recesses.

DEOXIDIZING ALUMINUM BAR

In the making of stainless steel, aluminum is used for deoxidizing the melt. Notched bars can be thrown into the ladle during pouring of the steel from an electric furnace, or an aluminum bar mounted on the end of a rod may be moved back and forth through the molten steel in the furnace until the bar dissolves. The bars that are used on rods are cast bars generally having a central cylindrical portion, from which a pair of side members or wings extend radially in opposite directions. Casting such a bar with a passage through its cylindrical portion for a supporting rod requires a mold with a core, which makes production of the bars more difficult and expensive than is desired.

It is among the objects of this invention to provide a deoxidizing aluminum bar which can be cast more cheaply than those used heretofore on rods, which can easily be made in a variety of shapes, and which also is suitable for use independently of a rod by being thrown into ladle receiving stainless steel.

The preferred embodiment of the invention is illustrated in the accompanying drawings, in which

FIG. 1 is a side view of our deoxidizing bar mounted on the lower end of a supporting rod;

FIG. 2 is a horizontal section taken on the line II—II of FIG. 1;

FIG. 3 is an exploded view of the two-part bar; and

FIG. 4 is a reduced side view of a mold, shown partly in section, in which one of the bar sections has been cast.

Referring to FIGS. 1 and 2 of the drawings, a cast aluminum two-part bar 1 is shown mounted on a rod 2, by which the bar can be stirred around in molten steel in an electric furnace in which stainless steel is being made. The steel, in melting the aluminum bar, will be deoxidized. The two parts or bar sections that form the bar are shown as being identical, although as will be pointed out later, they do not need to be. Each bar section is formed from a pair of laterally spaced parallel side members or wings 3 integrally connected by loop members 4 between them. Although one loop member could be used, it is preferred to use two. More than two are unnecessary. The two wings preferably lie in a common plane, but they could be inclined relative to each other. The loop members have their ends in the space between the wings, with which they are integral. The loop members project from what will be called the inner faces of the side members and are spaced apart a distance equal to the width of a loop.

As shown in FIG. 4, the bar section is cast in a permanent steel mold 8. The recesses 9 in the loop members are formed by a straight bar 10 resting in notches 11 in opposite sides of the mold. The bottom of this bar is curved transversely and the notches are shaped correspondingly. The loop members are shown as being arcuate, with the portions that project from the bottom of the side members semi-circular. Although this shape of loop member is preferred, it could take an angular form if desired. After a bar section has been cast in the mold it is a simple matter to remove it by merely lifting the bar 10 from notches 11 so that the mold can be inverted, allowing the cast bar section to fall free from the mold. There is no sand core that has to be extracted.

All of the bar sections are made the same but, as shown in FIG. 3, before they are assembled one of them is turned bottom-side up relative to the other and reversed so that the loop members of one bar section will be staggered relative to those of the other section, as also indicated in FIG. 1. The two sections are then assembled by moving them together to cause a loop of each section to be straddled by the two loops of the other section, and to bring the inner faces of the two pairs of wings into flat engagement with one another. By locating one loop member of each bar section at one end of the space between its wings and by making the wings wide enough so that the other loop will be spaced from the other end of the space between the wings a distance equal to the width of a loop, the two pairs of loop members will alternate relative to each other when the two bar sections are assembled and will not extend beyond the upper and lower edges of the wings when the bar is in the position shown in FIG. 1.

Assembly of the two bar sections results in the loops of each of them projecting from the outer faces of the wings of the other, as shown in FIG. 2, with their recesses 9 opening laterally in opposite directions and disposed end to end. When the rod 2 is inserted endwise through these recesses the two bar sections are locked together by it as shown in FIG. 1. To prevent the loop members from melting away before the side members are consumed and thereby releasing the side members from the supporting rod, the thickness of each loop member should be at least as great as the thickness of a side member and preferably greater.

If desired, the side members of one bar section may extend away from its loops a different distance than those of the other section. Or, the side members may be narrow bars, just wide enough to connect the pair of loop members between them. In such a case the deoxidizing bar will consist principally of the loop members. In some instances it may not be desirable to mount the bar sections on a rod at all. In that case they can be used in the manner that notched deoxidizing bars have been employed in the past. That is, the bar sections will not be assembled on a rod but will be merely dropped into a ladle of molten steel to deoxidize it.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. A deoxidizing aluminum bar comprising a pair of aluminum bar sections, each section having a pair of laterally spaced parallel side members with inner surfaces facing the inner surfaces of the other pair, and a pair of loop members disposed side by side in the space between said side members, one loop member having ends in said space integral with the side members of one of said bar sections, said loop member projecting from the outer faces of the other pair of side members, and the other loop member having ends in said space integral with the side members of the other bar section, said other loop member projecting from the outer faces of said side members of said one section, and said loop members forming recesses opening laterally in opposite directions and disposed end to end, and a rod inserted

lengthwise into said recesses whereby said two bar sections are locked together to form said bar.

2. A deoxidizing aluminum bar according to claim 1, including a second pair of said loop members integral with said side members in the same manner as the first pair of loop members, the two loop members joined to one pair of said side members alternating with the other two loop members.

3. A deoxidizing aluminum bar according to claim 1, in which said inner faces of one pair of said side members engage the inner faces of the other pair.

4. A deoxidizing aluminum bar according to claim 3, in which said inner faces of the side members are flat.

5. A deoxidizing aluminum bar according to claim 1, in which said side members are flat plates.

6. A deoxidizing aluminum bar according to claim 1,

in which the thickness of each loop member is at least as great as the thickness of said side members.

7. A deoxidizing aluminum bar according to claim 1, in which said loop members are U-shape and the inner walls of said recesses are arcuate.

8. A deoxidizing aluminum bar according to claim 2, in which said side members are flat plates.

9. A deoxidizing aluminum bar according to claim 8, in which said loop members are U-shape and the inner walls of said recesses are arcuate, and the thickness of each loop member is at least as great as that of said plates.

10. A deoxidizing aluminum bar according to claim 9, in which said side members are flat plates with the plates of each bar section disposed flat against the plates of the other bar section.
